UNITED STATES PATENT OFFICE.

ALBERT H. WOLAWSKY, OF SEYMOUR, CONNECTICUT.

COMBINATION COOKING-STOVE AND HEATER.

1,277,519.

Specification of Letters Patent.

Patented Sept. 3, 1918.

Application filed April 15, 1918. Serial No. 228,518.

To all whom it may concern:

Be it known that I, ALBERT H. WOLAWSKY, a citizen of Poland, residing at Seymour, county of Fairfield, State of Connecticut, have invented an Improvement in Combination Cooking-Stoves and Heaters, of which the following is a specification.

This invention has for its object to provide a combined cooking stove and heater, which, without complications in its structure, without adding materially to the cost of manufacture and without additional consumption of fuel, will fully meet the usual requirements of a cooking stove, and will 15 act as a hot air furnace and effectually heat one or more additional rooms.

With this object in view, I have devised the novel cooking stove and heater which I will now describe referring to the accompanying drawing forming a part of this specification and using reference characters to indicate the several parts.

Figure 1 is a perspective view, partly broken away, illustrating the construction and mode of operation of my novel stove, and

Fig. 2 is a horizontal section, looking down.

The special design and construction of the stove are immaterial so far as the present invention is concerned. I have shown the invention as applied to a cooking stove of ordinary construction and comprising a fire box having a grate 10, fire brick 11 on three sides thereof, and a water front 12 on the fourth side. The oven, indicated by 13, is provided at top, bottom, back and one side with a draft chamber 14.

The essential feature of novelty is an air heating chamber 15, which surrounds the fire box on four sides, lying outside the fire brick and the water front. The heating chamber is supplied with air by means of a pipe 16 which passes through the draft chamber under the oven, and is provided with an external opening 17 at the end of the stove opposite to the fire box. Opening 17 is provided with a damper 18 by which the supply of air to the heating chamber 40 may be regulated or wholly cut off as required. By causing the air supply pipe to pass through the draft chamber, the air in said pipe is preheated before it reaches the heating chamber. While in the heating

chamber, the circulation of the air is entirely free on all four sides of the chamber. As the air is preheated before it reaches the chamber, it will necessarily rise therein and will pass out by means of a hot air pipe 19, leading from the top of the chamber and provided with a damper 20, by which the volume of air passing from the heating chamber is controlled or is entirely cut off, as may be required. Supply pipe 16 is shown as leading into the heating chamber near one corner thereof, and the hot air pipe as leading therefrom at the corner diagonally opposite. I have shown but a single air supply pipe 16 and a single hot air pipe 19, but a plurality of supply pipes and a plurality of hot air pipes, either or both, may be used if preferred, these and other obvious details of construction being wholly within the scope of the invention. Where a plurality of rooms are to be heated, individual hot air pipes may lead to the several rooms or branch air pipes may lead from hot air pipe 19. 21 and 22 denote the usual cold and hot water pipes leading to and from the water front.

The operation of the invention is so simple as not to require description. In fact it is self operating. So long as neither damper 18 or 20 is wholly closed, air will pass through the supply pipe, will be preheated therein, and pass to the heating chamber, and will be further heated in the chamber and pass by means of the hot air pipe to the room or rooms to be heated.

Having thus described my invention, I claim:

A stove of the character described comprising a stove body provided with a fire box, an oven, a draft chamber under the oven, and a heating chamber surrounding the fire box and isolated from said draft chamber, an air inlet pipe passed through the draft chamber and leading direct to the lower portion of the heating chamber at one side of the stove, and a hot air delivery pipe leading from the heating chamber near the top thereof and at the other side of the stove, whereby the incoming air is caused to divide and pass on both sides of the fire box while traveling through the heating chamber.

In testimony whereof I affix my signature.

ALBERT H. WOLAWSKY.
